TUBE CAPPING APPARATUS

Eric L. Midgley, Salem, Mass., assignor to Sylvania Electric Products Inc., Salem, Mass., a corporation of Massachusetts

Application October 10, 1951, Serial No. 250,617

6 Claims. (Cl. 226—87)

1

This invention relates to the application of closures and more particularly to the application of pressure-sensitive closures to the ends of an elongated tube.

In the manufacture of fluorescent tubes, elongated glass tubes are provided with a coating of fluorescent powder on the inner walls thereof. Some of these tubes are further processed by the sealing of electrodes therein at the ends thereof to provide fluorescent lamps whereas other types of fluorescent tubes are capped and sold to sign manufacturers who seal electrodes to the tubes during the sign manufacturing operation. Heretofore, capping of the latter type of tubes has been performed manually by the insertion of stoppers, of cork for example, in the ends thereof. Manual capping in itself is a distinct disadvantage and prevents the development of high speed production schedules. However, the disadvantages which exist due to the use of stoppers as the closure device are of even greater importance because of their effects on the quality of the tubes. In some cases stoppers become dislodged during shipment of the tubes allowing dirt to enter and contaminate the fluorescent powder. Since stoppers are not necessarily air-tight, moisture gets into the tubes and has a deleterious effect on the fluorescent powder. In some cases it has been found that small particles of the stoppers have caused discoloration of the fluorescent coating to develop during the sign manufacturing operation thus rendering the tube unusable. Because of variations in the size of stoppers, some stoppers are inserted so far into the tubes that removal thereof is quite difficult whereas others are too large to be inserted far enough and tend to fall out or, if too much force is exerted to effect the insertion, the tube breaks.

An object of this invention is to provide tubes with an air-tight closure.

Another object is to affix an air-tight closure to the ends of a tube automatically.

A further object is to provide tubes with an air-tight closure, the application of which is not adversely affected by small variations in tube diameter within a given size.

A further object is to provide a tube capping apparatus which may be readily adjusted to permit capping of tubes of different diameters.

A further object is to provide a tube capping apparatus in which means are provided for automatically positioning the tube for the tube capping operations regardless of variations in tube length.

In accordance with the principles of my inven-

2

tion, a specific embodiment of which is shown in the accompanying drawings and described below, fluorescent tubes are indexed to a plurality of work stations on a conveyor where the tube capping operations are performed. At one of these stations a wafer of pressure-sensitive tape is punched from a supply thereof and affixed to one end of the tube. At a subsequent station the wafer is folded back into engagement with the wall of the tube and secured thereto. Subsequently, the same operations are performed on the other end of the tube.

In the specific embodiment of the tube capping apparatus illustrated in the accompanying drawings,

Figure 1 is a plan view of a tube capping apparatus showing several tube capping units disposed along the sides thereof.

Figure 2 is an end elevational view thereof looking in the direction of arrows 2—2 of Figure 1 showing the conveyor and tube capping actuating mechanisms.

Figure 3 is a fragmentary detail of the conveyor indexing mechanism taken along the line 3—3 of Figure 2, showing the relative disposition of the several members thereof upon completion of an index.

Figure 4 is an enlarged elevational view partly in section of one face of the tube capping mounting plate showing the tape feed and the wafer punching mechanism.

Figure 5 is an enlarged elevational view partly in section of the other side of the tube capping mounting plate showing the wafer wrapping mechanism and the tape feed indexing mechanism.

Figure 6 is an enlarged and elevational view of the tube capping mounting plate and the mechanisms associated therewith, looking in the direction of the arrows 6—6 of Figures 4 and 5.

Figure 7 is a fragmentary elevational view looking in the direction of the arrows 7—7 of Figure 1 showing the means for gripping the tubes during the tube capping operations.

Figure 8 is an enlarged front elevational view of the wafer wrapping head partly broken away to show the knurled rollers and associated parts.

Figure 9 is an enlarged sectional view of the wafer wrapping head taken along the line 9—9 of Figure 8.

Figure 10 is an enlarged fragmentary detail of an end of a tube with a wafer affixed to the end thereof by the punch shown particularly in Figure 4.

Figure 11 is an enlarged fragmentary detail of

an end of a tube with a wafer wrapped thereabout by the wafer wrapping head shown particularly in Figure 5.

In Figures 1 and 2 there is shown a conveyor which moves tubes 20 through a plurality of stations, including the tube capping stations. The conveyor comprises a pair of endless chains 22 and 24, with offset pins 26 upstanding thereon, traveling around sprocket wheels 28, 30, 32 and 34. A pair of asbestos strips 36 and 38, fixedly 5 mounted in position by means not shown, lie immediately above and in register with chains 22 and 24 respectively. The tubes 20 rest on the strips 36 and 38 and are caused to move thereacross by the pins 26 upstanding on the chains 15 22 and 24. Sprocket wheels 28 and 30 are mounted on idler shaft 40 supported in bearing brackets 42 mounted on one end of longitudinal angle iron members 44 and 46 respectively. Sprocket wheels 32 and 34 are mounted on driven shaft 48 supported in bearing brackets 50 mounted on the other end of longitudinal angle iron members 44 and 46 respectively. Members 44 and 46 are attached to and supported by standards 52.

Referring now particularly to Figure 2, motor 54, mounted on transverse angle iron member 56, has a sprocket wheel 58 mounted on the drive shaft 60 thereof. Chain 62 connects sprocket wheel 58 to sprocket wheel 64 mounted on conveyor drive shaft 66. As may be seen in Figure 1, the conveyor drive shaft 66 extends the length of the conveyor along the longitudinal axis thereof and is suitably supported by means which have been omitted for clarity of illustration. The conveyor drive shaft 66 has a cam 68 mounted thereon which is in engagement with cam roller 70 mounted on lever 72 intermediate its ends. Lever 72 is pivotally mounted at 74 in transverse angle iron member 76 and has one end of connecting rod 78 attached to its free end. Rod 78 connects lever 72 to arm 80 of bell crank lever 82. The bell crank lever 82 is provided with a hub 84 through which it is rotatably mounted on driven shaft 48. Arm 86 of bellcrank lever 82 has a pawl 88 mounted on the free end thereof which engages ratchet wheel 90 keyed to shaft 48.

Referring now particularly to Figure 1, rolls 92 are provided for shifting the tubes 20 laterally on the conveyor to position them accurately for the capping operation by moving them into endwise engagement with aligning plates 93 upstanding on angle iron members 44 and 46. Each of the several rolls 92 is disposed immediately beneath the tubes 20 and in engagement therewith. Since each roll 92 has its own actuating mechanism and since the actuating mechanism is substantially the same in construction in each case, only one will be described. Roll 92 is mounted on a shaft 94 (Fig. 2) supported in the upper part of bearing brackets 96 upstanding on transverse angle iron members 98. Shaft 94 is connected through a gear train (not shown) disposed on the inside faces of the bearing brackets 96 to a shaft 100 supported in the lower part of bearing brackets 96. Shaft 100 has a sprocket wheel 102 mounted thereon which is connected through chain 104 to sprocket wheel 106 mounted on the conveyor drive shaft 66. Although the several rolls 92 have a common drive, shaft 66, the gear trains disposed on the inside faces of the bearing brackets 96 are designed to provide for rotation of the rolls in the directions indicated by the arrows in Figure 1, i. e., adjacent rolls rotate in opposite directions, the purpose of which will be described below.

In order to obtain maximum tube capping production and to cap both ends of each tube, two or more tube capping units 107 are mounted in staggered relationship along each side of the conveyor as shown in Figure 1. Each unit 107 comprises a tape indexing mechanism, a punch mechanism for cutting a wafer from the tape, a wrapping mechanism for swirling the wafer about the end of the tube, and a gripping mechanism for holding the tube fixed during these operations.

The punch mechanism for cutting a wafer from a supply of tape is mounted on face 103 of mounting plate 110 which is attached to the side of the conveyor supporting framework (Figs. 1, 4 and 6). The tape indexing mechanism is mounted on face 112 of plate 110 as shown in Figures 2, 5 and 6. The wafer wrapping mechanism and the tube gripping mechanism are disposed adjacent to the face 112 of plate 110 but spaced therefrom (Figs. 1, 2, 5 and 6).

Since the several mechanisms of each tube capping unit 107 just mentioned are all driven by motor 54, that portion of the driving structure which is common to the several mechanisms will now be described, followed thereafter by a description of that portion of the structure which is not common. In Figure 2, the drive shaft 60 of motor 58 has a pair of sprocket wheels 114 mounted thereon. Since the connections to the right and to the left from sprocket wheels 114 are the same, only one will be described. Chain 116 connects one of the sprocket wheels 114 to sprocket wheel 118 on shaft 120 which is supported in bearing brackets 122 depending from a pair of transverse angle iron members of the conveyor supporting framework. Shaft 120 has a cam 124 which actuates the tube gripping mechanism and a sprocket wheel 126 mounted thereon. Cam 124 is engaged by cam roller 128 mounted on the free end of lever 130 pivotally mounted at 132 in transverse angle iron member 98. Sprocket wheel 126 is connected to sprocket wheel 134 on shaft 136 by chain 138. Shaft 136 extends through mounting plate 110 and is supported in bearing brackets 140 attached to the side of the conveyor supporting framework.

Shaft 136 (Fig. 2) has three cams mounted thereon, cam 142 for actuating the wafer wrapping mechanism, cam 144 for actuating the tape indexing mechanism and box cam 146 for actuating the wafer punching mechanism. A rocker shaft 148 extends through mounting plate 110 and is supported in a pair of bearing brackets 150 mounted on opposite faces of plate 110. Bell crank lever 152 and bell crank lever 154 (Figs. 2, 5 and 6) and lever 156 (Figs. 4 and 6) are mounted on rocker shaft 148. Bell crank levers 152 and 154 are provided with cam rollers 158 and 160 at one end thereof which are in engagement with cams 142 and 144 respectively. Lever 156 has a cam roller 162 at one end thereof which is disposed within the box cam 146.

The mechanism for gripping the tubes to hold them securely in position during the wafer-applying operation and the wafer wrapping operation will now be described. Referring now to Figures 1 and 2, the tube gripping mechanism comprises a pair of spaced lower plates 164 mounted on arm 166 attached to the top of tube 168 and an upper plate 170 disposed between spaced lower plates 164 and mounted on arm 171 attached to the top of rod 172 which extends through tube 168 and is movable therein. Plates 164 and plate 170 have co-operating cut-outs 174 formed therein

through which the tubes extend and in which they may be securely held. Referring now particularly to the tube gripping mechanism shown at the right in Figure 2, the lower end of tube 168 has a collar 176 attached thereto, to opposite sides of which one end of a pair of links 178 are connected. The lower end of rod 172 has a collar 180 attached thereto, to opposite sides of which one end of a pair of links 182 are connected. The other end of each of the two pairs of links 178 and 182 are pivotally connected at 184 to an end of yoke 186 through which rod 172 extends. The other end of yoke 186 is attached to an end of spring loaded rod 188 which is pivotally mounted on lever 130 at 190. The tube 168 is supported in proper vertical alignment by bearing 192 mounted on plate 194 attached to the side of standard 52.

The tape feed and its actuating mechanism will now be described. Referring now to Figure 4, a roll of tape 196 is mounted on feed drum 198 rotatably mounted on face 108 of plate 110. The tape 196 is fed around guide roll 200 mounted on shaft 202, then upwardly over pull roll 204 which has pins 206 projecting from the periphery thereof and which is mounted on shaft 208, and is finally wound on waste drum 210 mounted on shaft 212.

Referring now to Figure 5 which shows the face 112 of plate 110 on which the mechanism for actuating the tape feed is mounted, plate 214 is connected to bell crank lever 154 through pin 216 which is normally disposed in the position shown in L-shaped slot 218 in plate 214. Pin 220 on plunger 222 of solenoid 224 rides in slot 226 in plate 214. Connecting rod 228 connects plate 214 to bell crank lever 230 which is mounted on shaft 208 which extends through plate 110 from the other face thereof. Bell crank lever 230 has a pawl 232 mounted on one arm thereof which engages ratchet wheel 234 mounted on shaft 208. Link 236 connects the other arm of bell crank lever 230 to one arm of bell crank lever 238 mounted on shaft 202 which extends through plate 110 from the other face thereof. The other arm of bell crank lever 238 has a pawl 240 mounted thereon which engages ratchet wheel 242 mounted on shaft 202. Shaft 208 has a gear 244 mounted thereon adjacent to ratchet wheel 234. Gear 244 meshes with gear 246 which meshes with gear 248 which meshes with gear 250, gear 250 being mounted on shaft 252. Pulley 254 mounted on shaft 252 and pulley 256 mounted on shaft 212 which extends through plate 110 from the other face thereof are connected by belt 258.

The mechanism for punching a wafer from tape 196 will now be described. Referring now to Figures 4 and 6, link 260 connects lever 156 to punch 262 which rides in punch block 264 attached to face 108 of plate 110. Head 266 of punch 262 has a button 268 of resilient material such as rubber mounted on the front face thereof. The punch block 264 is provided with a transverse slot through which tape 196 passes. A cutting die 272 is mounted in punch block 264 adjacent to slot 270, so that when punch 262 is actuated a wafer 274 will be cut from the tape 196 and fed to the tube 20.

The mechanism for wrapping wafer 274 around an end of tube 20 will now be described. Referring now to Figures 1, 2 and 5, wafer wrapping head 276 is mounted on one end of shaft 278 which is supported in bearing bracket 280 mounted on face 112 of plate 110. The other end

of shaft 278 is connected to an arm of bell crank lever 152, the other arm of which has cam roller 158 attached thereto and in engagement with cam 142. Shaft 278 (Fig. 5) has a pulley 282 mounted thereon through key 284 in elongated slot 286. The key 284 fits loosely in slot 286 to permit reciprocation of shaft 278. Shaft 278 is rotatably driven by belt 288 which connects pulley 282 thereon to pulley 290 on shaft 120 through a pair of pulleys 292 mounted on face 112 of plate 110 and a pair of pulleys 294 mounted on transverse angle iron member 98 (Fig. 2).

Referring now to Figures 8 and 9, wafer wrapping head 276 comprises a plate 296 mounted on shaft 278 and a plate 298 which is maintained in frictional engagement with plate 296 by adjusting screw 300. Plate 298 has an elongated arcuate slot 302 (Fig. 6) therein through which adjusting screw 300 extends. Plate 296 has three slots 304 therein and plate 298 has three slots 306 therein, the slots 304 in plate 296 being partially in register with the slots 306 in plate 298. Plate 308, which has a central aperture 310 therein through which an end of tube 20 may extend, is mounted on plate 298 by means of three pivot pins 312. Three knurled rollers 314, disposed between plates 296 and 308, are rotatably mounted on roller pins 316, one end of each of these pins extending through a slot 304 and a slot 306 in plate 296 and plate 298 respectively, and being supported by plate 296. A pair of links 318 and 320 connects each of the roller pins 316 to one of the pivot pins 312. Each of the pivot pins 312 is provided with a torsion spring 322, one end of which is anchored in plate 296, the other end thereof being hooked around pin 324 mounted in and extending between links 318 and 320. Since the knurled rollers 314 are mounted on roller pins 316 to which the links 318 and 320 are connected, the torsion springs 322 urge the rollers 314 toward one another and hence into positive engagement with the end of the tube 20 when it is disposed therebetween.

Adjustment of the head 276 to accommodate tubes 20 of various diameters is made by loosening screw 300 and rotating plate 298 on plate 296. Rotation of plate 298 sets up a camming action with roller pins 316 riding on the wall 326 of slots 306 thus causing rollers 314 to move closer to or further away from one another depending on the direction of rotation of plate 298.

The operation of the tube capping apparatus will now be described. Tubes 20 are fed individually to asbestos strips 36 and 38 (Fig. 1) by some suitable means not shown where they are engaged by pins 26 upstanding on chains 22 and 24. Indexing of the chains 22 and 24 to effect movement of each tube 20 along the asbestos strips 36 and 38 to a plurality of stations is accomplished by motor 54 (Fig. 2) through drive shaft 60, sprocket wheel 58, chain 62, sprocket wheel 64, conveyor drive shaft 66, cam 68, cam roller 70, lever 72, connecting rod 78, bell crank lever 82, pawl 88, ratchet wheel 90, shaft 48 and sprocket wheels 32 and 34 around which chains 22 and 24 travel.

As was pointed out above, two or more tube capping units 107 may be mounted in staggered relationship along each side of the conveyor. In Figure 1 there are two such units on each side of the conveyor. The conveyor is indexed two stations at a time so that the first capping unit on each side thereof operates on one tube and the second capping unit on each side operates on the next tube. The operation of the tube

capping apparatus will be described with reference to the tube operated on by the first capping unit on each side of the conveyor, it being understood that the following tube is operated on in the same manner, by the second capping units.

As a tube 20 is moved from station A through station B to station C (Fig. 1), it engages the roll 92 which is rotating in the direction indicated by the arrow. Rotation of the roll 92 is effected by drive shaft 66 (Figs. 1 and 2) through sprocket wheel 166, chain 164, sprocket wheel 162, shaft 180, a gear train (not shown) on the inside face of bearing brackets 96, and shaft 94 on which roll 92 is mounted. At and between stations C and D, the tube 20 is moved endwise into engagement with aligning plate 93, thereby locating this end of the tube for the capping operations at subsequent stations.

The tube 20 is then indexed from station C to station E where a wafer 274 (Fig. 4) is punched from the roll of tape 196 and affixed to the end of the tube 20 as shown in Figures 4 and 10. However, before the wafer 274 is punched from the roll of tape 196, the tube 20 is gripped in the cutouts 174 in plates 164 and plate 170 (Fig. 7) mounted on arms 166 and 171 respectively which are attached to the top of tube 168 and rod 172 respectively (Figs. 1 and 2). Movement of the plate 164 upwardly and plate 170 downwardly is accomplished by the simultaneous upward movement of tube 168 and downward movement of rod 172. Actuation of tube 168 and rod 172 is effected by shaft 120 through cam 124, cam roller 128, rod 138, yoke 186 and links 178 and 182 which are connected to tube 168 and rod 172 respectively by collars 176 and 180 respectively. Shaft 120 is driven by motor 54 through motor drive shaft 60, sprocket wheel 114, chain 116 and sprocket wheel 118.

After the tube 20 is secured in position as just described, the punch 262 (Fig. 4) is driven forward and the head 263 thereof, in conjunction with the cutting die 272 cuts a wafer 274 from the tape 196 and affixes it on the adjacent end of tube 20, the resilient button 263 cushioning the blow against the end of the tube and preventing the metal head 263 from striking the tube and damaging it. Reciprocation of the punch 262 in the punch block 264 is effected by rotation of shaft 136 (Fig. 4), the motion being transmitted therefrom by box cam 146, cam roller 162, lever 156 and link 260 which is connected to the punch 262. Shaft 136 is driven by shaft 120 (Fig. 2) through sprocket wheel 134, chain 138 and sprocket wheel 126.

The tube 20, with the wafer 274 attached to the end thereof as shown in Figures 4 and 10 is then indexed from station E to station G where the wafer 274 is wrapped thereabout. During this indexing period the tape 196 is moved upwardly to present another portion thereof to the cutting die 272 and the punch 262 (Fig. 4). Unwinding of the tape 196 from the feed drum 188 and winding of the waste on waste drum 210 (Fig. 4) is effected by an indexing mechanism on the opposite face of plate 110 (Figs. 2 and 5) and is effected particularly by rotation of shaft 208 which has pull roll 204 mounted thereon on face 198 of plate 110 (Fig. 4) and ratchet wheel 234 mounted thereon on face 112 of plate 110. Shaft 208 is driven by shaft 138 (Fig. 5), the rotational movement of which is transmitted thereto through cam 144, cam roller 160, bell crank lever 154, plate 214, connecting rod 228, and bell crank lever 230 which is mounted on shaft 208 and

which has a pawl 232 attached thereto and in engagement with ratchet wheel 234.

Although advancement of the tape 196 may be accomplished by positively driving pull roll 204 only, better results may be obtained by positively driving waste drum 210, and even guide roll 203 if desired. Shaft 203 on which pull roll 204 is mounted is connected to shaft 212 on which waste drum 210 is mounted by gears 244, 246, 248 and 250, pulley 254, belt 258 and pulley 256 which is mounted on shaft 212 (Fig. 5). Shaft 203 on which pull roll 204 is mounted is connected to shaft 202 on which guide roll 200 is mounted by bell crank lever 238, link 236, bell crank lever 238, pawl 240 and ratchet wheel 242 which is mounted on shaft 202. Thus advancement of tape 196 may be effected by positively driving the waste drum 210 and the guide roll 200 as well as the pull roll 204.

If no tube is present, to which a wafer 274 may be attached, the tape 196 is prevented from indexing by energization of solenoid 224 (Fig. 5). Suitable conventional detecting means not shown are provided to register the absence of a tube and transmit this registration into energization of the solenoid to effect an upward movement of plunger 222 which has a pin 220 attached thereto and riding in slot 226 in plate 214. Retraction of the plunger 222 causes the pin 220 to tilt the plate 214 upwardly thus causing the pin 216 to drop down into the horizontal portion of L-shaped slot 218 in plate 214 and to ride therein during the power stroke of bell crank lever 154 instead of pushing the plate 214 forward.

At station G the wrapping head 273 (Figs. 1, 2, 5, 6, 8, and 9) is caused to move in, encircle the end of the tube 20, fold the wafer 274 back into engagement with the outer wall of the tube and swirl it thereabout to provide a capped tube as shown in Figure 11. Inward movement of the wrapping head 273 to encircle the end of the tube 20 and effect a folding of the wafer 274 back into engagement with the wall of the tube is effected by the shaft 273 on which the head is mounted. Shaft 273 is driven by shaft 133 through bell crank lever 152, cam follower 153, and cam 142 mounted on shaft 133. Swirling of the wafer 274 on the tube 20 is effected by the knurled rollers 314 which rotate with the shaft 273. Shaft 273 is rotated by shaft 120 (Fig. 2) through pulley 282, belt 283, pulleys 282, pulleys 294 and pulley 293 on shaft 120.

With this end of the tube 20 capped at Station G, the tube is advanced to station I (Fig. 1) where a second roller 92, rotating in the direction indicated by means described above, urges the tube into end-wise engagement with plate 93 adjacent to the first capping unit 107 on the other side of the conveyor. This capping unit then performs the same operations on this end of the tube as those already described with reference to the other end of the tube. The tube following the one on which the above-described operations have been performed is subsequently capped in the same manner by the second capping unit 107 on each side of the conveyor, after which all the capped tubes are removed therefrom either manually or mechanically by means not shown.

What I claim is:

1. Apparatus for effecting closure of articles comprising: a conveyor; means for indexing said conveyor to carry the articles to a plurality of work stations; a punch located at one of the work stations; means for indexing a tape transversely between said punch and the adjacent end of an

article at said station; means for reciprocating said punch to cut a wafer from the tape and affix it to the end of the article transversely thereof; a wafer-wrapping head located at a subsequent work station; and means for reciprocating said wafer-wrapping head into and out of engagement with the wafer on the end of the article to fold it back into contact with the side wall of the article.

2. Apparatus for effecting closure of articles comprising: a conveyor; means for indexing said conveyor to carry the articles to a plurality of work stations; a punch located at one of the work stations; means for indexing a tape transversely between said punch and the adjacent end of an article at said station; means for reciprocating said punch to cut a wafer from the tape and affix it to the end of the article transversely thereof; a wafer-wrapping head located at a subsequent work station; means for reciprocating said wafer-wrapping head into and out of engagement with the wafer on the end of the article to fold it back into contact with the side wall of the article; and means for gripping and retaining the article stationary during the wafer-affixing and wafer-wrapping operations.

3. Apparatus for effecting closure of articles comprising: a conveyor; means for indexing said conveyor to carry the articles to a plurality of work stations; means for automatically aligning the articles endwise with respect to the work stations; a punch located at one of the work stations; means for indexing a tape transversely between said punch and the adjacent end of an article at said station; means for reciprocating said punch to cut a wafer from the tape and affix it to the end of the article transversely thereof; a wafer-wrapping head located at a subsequent work station; and means for reciprocating said wafer-wrapping head into and out of engagement with the wafer on the end of the article to fold it back into contact with the side wall of the article.

4. Apparatus for effecting closure of articles comprising: a conveyor; means for indexing said conveyor to carry the articles to a plurality of work stations; means for automatically aligning the articles endwise with respect to the work stations; a punch located at one of the work stations; means for indexing a tape transversely between said punch and the adjacent end of an article at said station; means for reciprocating said punch to cut a wafer from the tape and affix it to the end of the article transversely thereof; a wafer-wrapping head located at a subsequent work station; means for reciprocating said wafer-wrapping head into and out of engagement with the wafer on the end of the article to fold it back into contact with the side wall of the article; and means for gripping and retaining the article

stationary during the wafer-affixing and wafer-wrapping operations.

5. Apparatus for effecting closure of both ends of an elongated tube, said apparatus comprising: a conveyor; means for indexing the conveyor to carry the articles to a plurality of work stations; means for automatically aligning the tubes endwise with respect to the work stations; a first tube-capping unit disposed at one side of said conveyor and a second tube-capping unit disposed at the opposite side of said conveyor and in staggered relation with respect to the first tube-capping unit, each of said tube-capping units comprising a punch in register with a tube at one of the work stations, means for moving a tape transversely between said punch and the adjacent end of the tube, means for reciprocating said punch to cut a wafer from the tape and affix it to the end of the tube transversely thereof, and means at a station subsequent to the station at which said punch is located for folding the wafer back into engagement with the side wall of the tube.

6. Apparatus for effecting closure of both ends of an elongated tube, said apparatus comprising: a conveyor; means for indexing the conveyor to carry the articles to a plurality of work stations; means for automatically aligning the tubes endwise with respect to the work stations; a first tube-capping unit disposed at one side of said conveyor and a second tube-capping unit disposed at the opposite side of said conveyor and in staggered relation with respect to the first tube-capping unit, each of said tube-capping units comprising a punch in register with a tube at one of the work stations, means for moving a tape transversely between said punch and the adjacent end of the tube, means for reciprocating said punch to cut a wafer from the tape and affix it to the end of the tube transversely thereof, and means at a station subsequent to the station at which said punch is located for folding the wafer back into engagement with the side wall of the tube; and means for gripping and retaining the tubes stationary during the wafer-affixing and wafer-wrapping operations.

ERIC L. MIDGLEY.
